(57) **CLAIM**

The ornamental design for a radiator grill for a vehicle, as shown and described.

DESCRIPTION

FIG. 1 is a right side perspective view of a radiator grill for a vehicle showing our new design with the slats in a closed position, to which the left perspective view is a mirror image;

FIG. 2 is a front elevation view of a radiator grill for a vehicle with the slats in a closed position;

FIG. 3 is a right side perspective view thereof with slats in an opened position, to which the left side perspective view is a mirror image; and,

FIG. 4 is a front elevation view of a radiator grill for a vehicle with the slats in an opened position.

The broken lines showing portions of a vehicle are for the purpose of illustrating environmental structure and form no part of the claimed design.
